UNITED STATES PATENT OFFICE

23,248

PREPARATION OF SUBSTITUTED
ALKYLOLTETRAHYDROPYRAN

William F. Gresham and William E. Grigsby, Wilmington, Del., assignors to E. I. du Pont de Nemours & Company, Wilmington, Del., a corporation of Delaware

No Drawing. Original No. 2,493,964, dated January 10, 1950, Serial No. 782,030, October 24, 1947. Application for reissue April 20, 1950, Serial No. 157,191

8 Claims. (Cl. 260—338)

Matter enclosed in heavy brackets **[( )]** appears in the original patent but forms no part of this reissue specification; matter printed in italics indicates the additions made by reissue

1

This invention relates to a process for preparation of tetrahydropyrans, and more particularly to the preparation of alkylol substituted tetrahydropyrans from an aldehyde and a 1,3-diene.

One object of the invention is to provide a process for the preparation of new compositions of matter. Another object is to provide a process for the preparation of alkylol substituted hydroxy tetrahydropyrans by the interaction of an aldehyde with a 1,3-diene and especially butadiene. Still another object is to provide a process for the preparation of alkylol substituted hydroxy tetrahydropyrans by the reaction of formaldehyde with butadiene. Yet another object is to provide conditions for effecting the reaction while at one and the same time inhibiting the polymerization of the butadiene. Other objects and advantages of the invention will hereinafter appear.

The above and other objects are accomplished by reacting an aldehyde such as formaldehyde with a 1,3-diene such as butadiene in the presence of an acid condensation catalyst and a polymerization inhibitor. These alkylo and formal substituted tetrahydropyrans are obtained from formaldehyde and butadiene **[(s.)]**:

[(1)] 3 - hydroxy - 4 - methyloltetrahydropyran and **[(2)]** its formal:

Due to the presence of two asymmetric carbon atoms (carbon atoms #3 and #4) in each of the above compounds, stereoisomers are possible. In addition these structural isomers appear to be formed.

2

[(3)] 4 - hydroxy-3-methyloltetrahydropyran and **[(4)]** its formal:

These compounds also, due to the presence of asymmetric carbon atoms (#3 and #4), may likewise exist in stereoisomeric forms. An intermediate product is likewise obtained, viz. 4-vinyl-1,3-dioxane,

having a boiling point of 142° C. Inasmuch as this intermediate can be reconverted to the desired product, it can be recycled and by this means the desired product produced in the substantial absence of these intermediates.

Examples are given describing the preferred embodiments of the invention in which parts are by weight unless otherwise stated.

Example 1.—A charge of 134.4 grams H₂O, 3.8 grams H₂SO₄, 0.2 gram hydroquinone, 40.8 grams paraformaldehyde and 24 grams butadiene was processed in a 325 ml. silver-lined shaker tube at 121–135°/4 hrs., during which time the autogenous pressure fell from 250.20 p. s. i. the discharge (200.4 grams, light brown liquid) contained 17.5% of the charged CH₂O, of which amount 71% was recovered in the distillate. The discharge was carefully neutralized with NaOH and distilled. The first cut (85–100°, 182.4 grams) contained an upper layer of 6 cc. of intermediate products including 4-vinyl dioxane-1,3. The next cut was the formal of **[(3)-hydroxy-4-methyloltetrahydropyran,]** **[(4) - hydroxy-3-methyloltetrahydropyran,** 18.6 grams. This substance boils at 79°/10 mm. or 56°/2 mm., has a refractive index (as a supercooled liquid) of 1.4668 at 25° C. It is a crystalline, water-soluble solid, melting

3

at 55° (ex ether or cyclohexane). The remainder, 18.6 g., boiled at 98–124° C. at 1 mm. pressure. Redistillation of this fraction gave a pure compound boiling at 120° C./1 mm. This glycol is a viscous, water-soluble, nearly colorless oil with a refractive index of 1.4863 at 25°. The residue was 9.7 g. or 3.7 g. net (allowing for Na₂SO₄).

4

unchanged formal and 11.1 g. of [3-hydroxy-4-methyloltetrahydropyran] 4-hydroxy-3-methyloltetrahydropyran.

Example 5.—A 37 g. fraction boiling below 115° C./1 mm. and a 20.3 g. fraction boiling higher than what was believed to be [3-hydroxy-4-methyloltetrahydropyran] 4-hydroxy-3-methyloltetra-

	[3-Hydroxy-4-methyloltetrahydropyran]	[Formal of 3-Hydroxy-4-methyloltetrahydropyran]		
	4-Hydroxy-3-methyloltetrahydropyran	Formal of 4-Hydroxy-3-methyloltetrahydropyran	Water Insoluble Layer Considered as Δ-3-Dihydropyran	Total
Conv. (based on C ₄ H ₆)	Per cent 31.1 26.4	Per cent 29.1 36.4	Per cent 16.1 6.7	Per cent 76.9 71.5
Yield (based on consumed CH ₂ O)				

Example 2.—The aqueous fraction from Example 1, including the upper layer, was recycled with make-up CH₂O, H₂SO₄, hydroquinone, and butadiene under the same conditions (121–125°/4 hrs./320–59 p. s. i.). Unconverted formaldehyde amounted to 25.6%. The product was analyzed as described in Example 1. The upper layer of the aqueous distillate was 16 cc. (an increase of 10 cc. over the charged amount).

hydropyran (B. P. ca. 120° C./1 mm.) was boiled at atmospheric pressure with 155.4 g. of water and 10.8 g. of H₂SO₄ for 7.5 hours. Neutralization of the H₂SO₄ with caustic and distillation gave 20.0 g. of [3-hydroxy-4-methyloltetrahydropyran] 4-hydroxy-3-methyloltetrahydropyran. (Either isomerization or/and hydrolysis of formals occurred yielding the above compound.)

30 Example 6.—A mixture comprising 202.5 g. H₂O,

	[3-Hydroxy-4-methyloltetrahydropyran]	[Formal of 3-Hydroxy-4-methyloltetrahydropyran]		
	4-Hydroxy-3-methyloltetrahydropyran	Formal of 4-Hydroxy-3-methyloltetrahydropyran	Water Insoluble Layer Considered as Δ-3-Dihydropyran	Total
Conv. (based on C ₄ H ₆)	Per cent 23.0 21.3	Per cent 36.3 50.3	Per cent 26.8 12.4	Per cent 86.1 84.0
Yield (based on consumed CH ₂ O)				

Example 3.—The aqueous distillate containing 16 cc. of upper layer obtained in Example 2 was processed with make-up formaldehyde (12.7 g.) and 4.4 g. of H₂SO₄ in the absence of butadiene at 160–163° C. for 1 hour. Distillation of the

45 8.8 g. conc. HCl, 0.3 g. hydroquinone, 62.1 g. paraformaldehyde, and 27 g. butadiene was processed at 123–130°/3 hrs./410–150 p. s. i. (autogeneous pressure). The product was analyzed as described in Example 1.

	[3-Hydroxy-4-methyloltetrahydropyran]	[Formal of 3-Hydroxy-4-methyloltetrahydropyran]		
	4-Hydroxy-3-methyloltetrahydropyran	Formal of 4-Hydroxy-3-methyloltetrahydropyran	Water Insoluble Layer Considered as Δ-3-Dihydropyran	Total
Conv. (based on C ₄ H ₆)	Per cent 25.1 17.3	Per cent 42.5 43.8	Per cent 7.2 2.5	Per cent 74.8 63.6
Yield (based on consumed CH ₂ O)				

product, after neutralization of the H₂SO₄ with aqueous caustic, gave 6.8 g. of the formal of [3-hydroxy-4-methyloltetrahydropyran] 4-hydroxy-3-methyloltetrahydropyran and 14 g. of [3-hydroxy-4-methyloltetrahydropyran] 4-hydroxy-3-methyloltetrahydropyran.

Example 4.—A reaction mixture comprising 20.0 g. of the formal of [3-hydroxy-4-methyloltetrahydropyran] 4-hydroxy-3-methyloltetrahydropyran, 275.7 g. of water and 5.0 g. of H₂SO₄ was processed at 122–134°/C. for 2 hours. Neutralization and distillation of the product gave 3.3 g. of

65 70 Example 7.—A mixture consisting of 116.6 g. acetic acid, 3.5 g. H₂SO₄, 0.2 g. hydroquinone, 24 g. butadiene, 42.0 g. paraformaldehyde, 26.2 g. H₂O was processed at 118–125°/4 hrs. Titration of the discharge showed that 7% of the CH₂O was unconverted. Enough NaOH was added (3 g.) to neutralize the H₂SO₄ and the water and acetic acid were removed by distillation. The first cut was 28.1 g. of the solid formal of [3-hydroxy-4-methyloltetrahydropyran] 4-hydroxy-3-methyloltetrahydropyran. The second cut, 5.3 g., boiled from 61°/1.5 mm. to 96.5°/1.5 mm., while

the next fraction, 4.9 g., had a boiling range of 98.5-101°/1.5 mm., and a refractive index (25°) of 1.4618. The final cut, B. P. 107-140°/1.5 mm. weighed 10.5 g. The net residue was 3 g. The formal was produced in 44% conversion (based on C₄H₆) and 47.3% yield (based on CH₄O consumed). The higher boiling fractions are esters and are assumed to contain the mono- and diacetates of [3-hydroxy-4-methylolethyltetrahydropyran] 4-hydroxy-3-methylolethyltetrahydropyran.

This example illustrates, inter alia, that when an organic acid such as acetic acid is used as a diluent in place of water, esters are obtained as well as the cyclic formal. Upon analysis the properties of the products were found to be as follows:

3		

Generally speaking, the afore-illustrated reactions may be conducted at temperatures between 100° and 200° C. with an optimum range between 120° and 130° C. A higher temperature tends to give greater tar formation and wider by-product distribution. The reaction is conducted at these temperatures for processing times ranging from 15 minutes (at 150° C.) to 6 hours (at 120° C.); a four-hour reaction time gave purer [3-hydroxy-4-methylolethyltetrahydropyran] 4-hydroxy-3-methylolethyltetrahydropyran.

The ratio of formaldehyde to butadiene may range from 1 to 6 moles of formaldehyde per mole of butadiene, although the optimum is 3 or more moles formaldehyde per mole of the butadiene. The formaldehyde concentrations should range between 10 and 40% of the total charge with optimum concentrations between 15 and 25%.

Other aldehydes may be used such as acetaldehyde, propanal, the butanals, and the higher straight and branched chain aldehydes. These aldehydes, as well as formaldehyde may be reacted, (in accord with the invention with the proportions and operational procedures used for the formaldehyde-butadiene reaction) with 1,3-dienes other than butadiene such as, 2-methyl, 1,3-butadiene, 2-ethyl 1,3-butadiene and the like.

Any suitable acid condensation catalyst may be employed such, for example, as hydrochloric acid, phosphoric acid, boron trifluoride (either alone or as a complex with water or aldehyde), aromatic sulfonic acids, or other strongly acid condensation catalysts. The catalysts should be employed in concentrations equivalent to the concentration of sulfuric acid when it is used, i. e., concentrations between 0.5 and 8% of the total charge, and optimum ratios from 1.25 to 2% of sulfuric acid.

Any suitable form of formaldehyde may be used such, for example, as 37% aqueous formaldehyde (known commercially as Formalin), paraformaldehyde, or trioxane. Polymerization

cyclic formals and 4-vinyl-1,3-dioxane which comprises reacting at least one mol of formaldehyde per mol of butadiene in the presence of a polymerization inhibitor and an acidic condensation catalyst at a temperature between 100 and 200° C. and under autogenous pressure.

2. The process of claim 1 conducted with a ratio of from 1 to 6 moles of formaldehyde per mole of butadiene.

3. The process of claim 1 in which from 10 to 40% of formaldehyde is used based on the total charge.

4. A process for the preparation of [3-hydroxy-4-methyloletetrahydropyran] 4-hydroxy-3-methyloletetrahydropyran which comprises reacting from one to six mols of formaldehyde per mol of butadiene in the presence of water, a polymerization inhibitor and an acidic condensation catalyst at a temperature between 100° and 200° C., neutralizing the catalyst and recovering the [3-hydroxy-4-methyloletetrahydropyran] 4-hydroxy-3-methyloletetrahydropyran after distilling off the formal of [3-hydroxy-4-methyloletetrahydropyran] 4-hydroxy-3-methyloletetrahydropyran.

5. A process for the preparation of the formal of [3-hydroxy-4-methyloletetrahydropyran] 4-hydroxy-3-methyloletetrahydropyran which comprises reacting from one to six mols of formaldehyde per mol of butadiene in the presence of water, a polymerization inhibitor and an acidic condensation catalyst at a temperature between 100° and 200° C., neutralizing the catalyst and recovering the formal of [3-hydroxy-4-methyloletetrahydropyran] 4-hydroxy-3-methyloletetrahydropyran by distillation.

6. A process for the preparation of 4-vinyl-1,3-dioxane which comprises reacting from 1 to 6 mols of formaldehyde per mol of butadiene in the presence of a polymerization inhibitor and an acidic condensation catalyst at a temperature between 100° and 200° C., neutralizing the catalyst and separating from a distillation cut between 85° and 100° C. the 4-vinyl-1,3-dioxane.

[7. 4-vinyl-1,3-dioxane.]

[8. An alkylol substituted tetrahydropyran, produced by reacting formaldehyde with butadiene in the presence of water, a polymerization inhibitor and an acidic condensation catalyst at a temperature between 100 and 200° C., boiling at 290-291° C. and 760 mm., having a specific gravity of 1.175 and a refractive index at 25° C. of 1.4867.]

[9. A formal substituted tetrahydropyran, obtained by reacting formaldehyde with butadiene in the presence of water, a polymerization inhibitor and an acidic condensation catalyst at a temperature between 100 and 200° C., having a melting point of 55° C., a boiling point of 79° C. at 10 mm., and a refractive index of 1.4668 at 25° C.]

10. The product, 4-hydroxy-3-methyloletetrahydropyran, having approximately these properties: boiling at 290-291° C. at 760 mm., having a specific gravity of 1.175 at 25° C. and a refractive index at 25° C. of 1.4867.

11. The formal of 4-hydroxy-3-methyloletetrahydropyran, having approximately these properties: a melting point of 55° C., a boiling point of 79° C. at 10 mm., a refractive index (as a supercooled liquid) of 1.4668 at 25° C. and the formula:
